UNITED STATES PATENT OFFICE.

HENRY HEININGER, OF ORANGE, NEW JERSEY, AND WILLIAM UNGER, OF NEW YORK, N. Y.

DESIGN FOR A DISPLAY-CARD.

SPECIFICATION forming part of Design No. 34,530, dated May 21, 1901.

Application filed April 19, 1901. Serial No. 56,668. Term of patent 3½ years.

To all whom it may concern:

Be it known that we, HENRY HEININGER, a subject of the Emperor of Germany, and a resident of Orange, in the county of Essex and State of New Jersey, and WILLIAM UNGER, a citizen of the United States, and a resident of the city of New York, borough of Manhattan, in the county and State of New York, have invented and produced a new and original Design for a Display-Card, of which the following is a description, reference being had to the accompanying drawing, forming a part thereof, in which is represented a front elevation of a display-card embodying the features of our design.

The leading features of the design consist in a card A, upon which a strip A' is apparently secured, bearing bars of music B. A representation of a nursing-bottle C is apparently secured to the card by a bow C', and there is also a representation of a crying baby D, a representation of a rattle E, a diaper F, a slipper G, and a section of carpet F', upon which tacks F² appear.

The minor features of the design consist in the cord support H for the card, which cord support is decorated at the front of the card

by loops H', which appear in the nature of bows, together with the particular arrangement of the parts described as the leading features, wherein the strip bearing the bars of music is at the upper portion of the card, the representation of the crying baby at the upper central portion of the card, the nursing-bottle and rattle being placed at opposite sides of the crying baby and the section of carpet and the diaper below the representation of the crying baby, and the representation of the slipper is at one side of the lower portion of the card.

Having thus described our invention, we claim as new and desire to secure by Letters Patent—

The design for a display-card herein shown and described.

In testimony whereof we have signed our names to this specification in the presence of two subscribing witnesses.

HENRY HEININGER.
WILLIAM UNGER.
